CANISTER BIN UNIT

Elizabeth Byington Manning, Shaker Heights,
and Anthony von Haase, Parma Heights, Ohio;
said von Haase assignor to said Manning

Application March 12, 1947, Serial No. 734,286

2 Claims. (Cl. 312—296)

1

This invention relates to storing and dispensing devices and in particular to canister bin units such as are used for the storing and dispensing of bulk food commodities in the home.

Canister units for storing relatively small quantities of bulk food articles such as sugar, flour, coffee, rice, beans, barley, and the like are frequently used in the home kitchen and can be procured in numerous designs. Some are boxes with hinged covers, others are cylindrical cans with friction covers, and still others are of the bin type. It is one of the principal objects of the present invention to provide a generally improved bin-type kitchen canister unit having individual bins which can be removed from the unit for individual use and for cleaning and filling the same. More specifically the invention aims to provide such a canister unit which includes a casing having an opening through which a bin may be inserted into the casing, the bin having a primary closure and, in addition, a secondary closure or seal is provided for the bin by cooperating parts of the bin and the casing.

Another object is to provide an improved pivot means for use in a canister casing and bin combination of the type in which the pivot parts are disposed intermediate the side walls of the bin, so that the removal and inserting of the bin into the casing is facilitated and a seal can be established between the bin and the casing.

Another object is to provide in a casing and bin combination an improved arrangement wherein the bin carries a closure for the casing opening and the bin is so mounted that its weight gravitationally retains the closure in sealing engagement with the casing.

Another object is to provide a kitchen canister bin unit of sheet metal construction so arranged as to be receivable between the conventional studding of a house for recessing of the unit into a kitchen wall.

Other objects and advantages of the invention having to do with certain novel arrangements, combinations of parts, and features of construction will become apparent from the following detailed description of a suitable embodiment of the invention. This description is made in connection with the accompanying drawings wherein:

Figure 1 is a front elevational view of a canister bin unit;

Fig. 2 is a sectional view through the canister unit taken substantially on the line 2—2 of Fig. 1 and enlarged with respect to that figure, this view showing the bin in tilted dispensing position by broken lines;

2

Fig. 3 is a sectional view with parts broken away and removed taken substantially on the line 3—3 of Fig. 1 and enlarged with respect to that figure;

Fig. 4 is a top view of the bin with parts removed showing the slidable closure thereof;

Fig. 5 is a sectional detail taken substantially on line 5—5 of Fig. 3 and enlarged with respect to that figure;

Fig. 6 is a sectional detail showing the bin closure seal taken substantially on the line 6—6 of Fig. 4 and enlarged with respect to that figure;

Fig. 7 is a sectional detail taken substantially on the line 7—7 of Fig. 4 and enlarged with respect to that figure showing the seal along the front edge of the bin slidable closure.

The canister bin unit illustrated in the drawings comprises a casing accommodating two bins. The over-all width of the casing is made 14 inches so that it is receivable between house studding located on 16 inch centers. Units having more than two bins may be made for counter use or for recessing in walls having studding on 24 inch or other centers. The individual bins may also be made relatively smaller. In the description of the unit reference is made to the drawings by numerals of reference which indicate like parts throughout the several views.

The casing, preferably formed of a relatively thin sheet metal such as about 18 to about 22 gauge sheet steel, comprises a body portion A and identical end caps B. The single sheet or piece of sheet metal forming the body A of the casing is bent along three spaced parallel lines forming upper and lower front corners 1 and 2 and upper rear corner 3 thereof. The edges of the sheet are brought together at the lower rear corner of the casing, that portion of the sheet forming bottom 4 of the casing having an up-standing flange 5 disposed flatwise against rear wall 6 and soldered or welded thereto.

The central portion of the top wall 7 overlying each of the bins is offset upwardly or characterized and is receivable within a mating recess formed by offsetting a like portion of each of the bottom walls 4 so that a number of the canister units can be stacked one on top of another and the matching offset and recessed portions interfitted to retain the several units in predetermined aligned relation. The recessing of the central portions of the bottom wall 4 provides relatively narrow footing portions 8 along outer edges of the casing and across the center thereof from front to rear between adjacent bin compartments. When a plurality of the canister units are stacked

these bearing portions 8 are received on narrow footings 9 about the edges of the characterized top wall 1. The charactering of the top and bottom walls thus provides an interfitting of the parts which resists displacement of the bearing portions on the footings.

The caps B are disposed across the ends of the casing A. These caps are formed, as by stamping, of imperforate sheet metal and have narrow peripheral flanges 10 which overlie the end edges of the casing walls to which they are secured by soldering or welding.

In front wall 11 of the casing are rectangular openings which receive bins C. Each of the bins is formed of sheet metal of about 18 to about 22 gauge and is of generally rectangular form in plan to occupy a maximum amount of the available space within the casing A.

The major parts of the bin are conveniently formed of a single sheet of metal, the central portion of the metal constituting bottom wall 14 and side and rear walls 15 and 16 being formed of outlying portions of the sheet bent upwardly along the side and rear edges of the bottom 14. The edges of the sheet metal meeting along the corners of the bin walls are joined by soldering or welding.

Front wall 17 of each bin is formed of a separate piece of sheet metal having a rectangular shape corresponding to but slightly larger than one of the rectangular openings in the front wall 11 of the casing. The front portion of the bottom bin wall 14 includes an upwardly directed inwardly curved or concave portion 18 which terminates in an upwardly directed flange 19 soldered or welded to the rear of the front wall 17. The side walls 15 of the bin have inwardly directed flanges 20 (Fig. 3) along their front edges which are soldered or welded to the rear of the front wall 17. The front wall 17 extends laterally beyond the side walls 15 of the bin and also depends below the flange 19 on the concave portion 18 of the bottom wall 14. It does not, however, extend below the plane of the bottom wall 14 of the bin. Thus the peripheral margins of the front wall 17 of each bin are made to overlie the edges of the front wall surrounding the corresponding rectangular opening therein. The edges of the front bin receiving openings are offset inwardly as indicated at 21 and a sealing gasket 22 of resilient deformable material such as sponge rubber is cemented against the offset margins and against the shoulder thereof. The marginal edges of the front bin wall 17 make sealing contact with the rubber gasket around the entire periphery of the front opening.

A recess or concavity is provided across the front of the bin behind the lower edge of the front wall 17. This recess is defined by the concave portion 18 of the bin bottom and accommodates means for pivotally supporting the bin inside the casing. Elongated pivot bar or member 24 is disposed in the recess in parallel relation to the line of intersection of the planes of the front wall 17 and the bottom 14 of the bin and is located wholly within the angle of the front and bottom walls.

The pivot bar is secured to the bin so as to support the latter by means of bracket element 25. These brackets are apertured to receive the pivot bar 24 which is secured in place by a press fit or by being soldered or welded. Flanges 26 on the brackets 25 conform to the shape of the concave wall portion 18 and are secured thereto in spaced apart relation by welding or soldering.

The ends of the pivot bar 24 extend beyond the bracket elements 25 and are received in cradles 27 disposed in the angle between the front wall 11 and the bottom 4. The cradles may be of cast metal or made by a stamping operation out of sheet metal and comprise an upright body portion having bottom and front flanges 28 and 29 which are disposed flatwise against and soldered or welded to the bottom 4 and the front wall 11 of the casing. Each of the cradles is formed with a tapered or V-shaped notch opening through the top edge of the upright body portion and arranged to receive and support one of the ends of the pivot pair 24. An angularly disposed reinforcing flange 30 is formed along the rear edge of the notch to reduce wear and to stiffen the cradle.

The cradles 27 and the pivot bar 24, together with the bracket elements 25, comprise a pivotal support for the bin which is located wholly in the recess along the bottom front corner of the bin and provides a pivot axis coinciding with the longitudinal axis of the bar 24 located in the angle between the front wall and the bottom of the bin. The pivot support assembly permits the bin to be swung from closed position, illustrated by the solid lines of Fig. 2, to an open or dispensing position, illustrated by the broken lines of that figure. The relative positions of the parts when the bin is in dispensing position is also illustrated in solid lines in Fig. 5, the broken lines of the latter figure showing the closed position of the bin. As the bin is swung to open position on its pivot axis, the upper edges of the bracket elements 25 engage the front wall 11 along the bottom of the casing opening, thus limiting the forward movement of the bin.

The top of the bin curves upwardly and forwardly from the upper edge of the rear wall 16, the center of curvature being along the pivot axis of the bin which coincides with the axis of the pivot bar 24. The top includes a curved panel portion 31 which may be an integral extension of the rear wall 16 and which extends across the entire width of the bin, being marginally secured as by welding or soldering to the curved upper edges of the side walls 15. The panel portion 31 covers the rear half of the bin and the front half is covered by an arcuate closure panel 32 conforming to the curvature of the rear panel 31 and riding on guides 33. The guides 33 are each metal strips of angle section bent to conform to the curvature of the rear top panel portion 31. These guides each have one flange secured by welding or soldering to the inside of one of the side walls 15 and the other flange thereof is disposed in spaced confronting relation to the inside of the top rear panel 31 so as to receive the closure panel 32 therebetween when the latter is moved to open position, shown by the broken lines of Fig. 2. The guides 33 extend forwardly in a continuous curve to adjacent the front wall 17 and the side edges of the closure 32 are supported thereon when drawn forwardly to closed position shown by the full lines of Fig. 2.

Along the under side of the front marginal edge of the curved closure 32 is a sealing strip 35 of resilient deformable material such as rubber held in place by a metal strip 36 soldered or welded to the underside of the closure and having an offset portion which clamps the rubber sealing strip in place.

A rubber sealing strip 37 is disposed along the upper marginal edge of the rear panel portion 31 and extends beyond such edge for sliding en-

gagement with the upper surface of the closure 32. The rubber seal 37 is held in place by a metal strip 38 soldered or welded to the top of the panel portion 31 and having an offset portion which overlies the rubber sealing strip to clamp and retain the latter in place. Rubber sealing strips 39 corresponding in shape and function to the rear sealing strip 37 are disposed along the sides of the top opening of the bin and are held in place by metal strips 40 corresponding to the strips 38 that hold the rear seal. The side strips 40 may be welded or soldered to the side walls 15 of the bin along the upper edge corners thereof or they may have depending flanges which are disposed flatwise against and secured to the inside top margins of the side walls.

An angle member 42 is secured to the top of the curved closure 32 adjacent to the front edge thereof and serves as a handle or pull for manually sliding the closure back and forth. When in closed position, as shown by the full lines of Fig. 2 and in Fig. 4, the closure 32 provides a tight primary seal for the rectangular opening in the top of the bin, the several deformable rubber gaskets or seals extending around the entire periphery of the bin opening and preventing the entrance of moisture, insects, and vermin into the interior of the bin.

When the bin is tilted forward to the open or dispensing position, illustrated by the broken lines of Fig. 2, a latch 43 of spring metal engages the front wall 11 of the casing at the top of the front opening. The latch is secured at one end to the central portion of the strip 38 and extends rearwardly therefrom. The other end of the latch is bent to U-shape with the opening directed upwardly. One leg 44 of the latch engages behind the front wall 11 at the top of the casing opening to limit the forward pivoting or tilting movement of the bin, other leg 45 of the latch engages the outside of the front wall 11 (or the gasket 22 overlying the same) to retain the bin in dispensing position. When it is desired to return the bin to closed position, pressure is applied manually to the latch 43 so as to depress the leg 45 below the edge of the front wall 11 and allow the bin to be pivoted into the casing.

A handle or pull 46 secured to the front wall 11 of the bin adjacent to the top thereof provides a hand hold for tilting the bin forward and for lifting the bin out of the casing. When the bin is to be withdrawn from the casing, as, for example, if it is desired to use the contents in another part of the room or to replenish the same, the bin is first tilted forward to the dispensing position and pressure is applied to the latch 43 to depress the same and release the leg 44 thereof from behind the casing wall. The bin is then lifted upwardly and forwardly, withdrawing the pivot bar 24 from the cradles 27 and freeing the bin so that it can be removed bodily from the casing through the front opening thereof.

When the bin is withdrawn from the casing the curved closure 32 of the bin maintains the primary seal and prevents the entrance of moisture, insects, and dust. Accordingly, the bin can be withdrawn from the casing for long periods of time without danger of objectionable contamination of the bin contents.

To replace the bin in the casing the bin is inserted bottom foremost through the rectangular opening in the front of the casing and the

pivot bar 24 is fitted into the cradles 27. The rear portions of the cradles 27 are higher than the front portions, the pivot engaging flanges 30 extending upwardly substantially to the level of the offset portion of the front wall 11 along the bottom of the casing opening. Edges 48 along the front portions of the cradles 27 slant downwardly and rearwardly so as to engage the pivot bar 24 and move the latter rearwardly as the bin settles into position in the casing. The inclined edges 48 of the cradles serve to draw the marginal edges of the bin front 17 snugly against the deformable gasket 22 to provide an effective seal. The weight of the bin and the contents thereof, carried solely by the pivot bar 24 journaled in the cradles 27, acts to draw the front wall tightly against the gasket 22 around the entire margin of the front opening of the casing thereby preventing objectionable moisture, dirt, insects and the like from entering the casing. The front door thus provides an effective secondary seal for the bin.

The principles of the present invention may be utilized in various ways, numerous modifications and alterations being contemplated, substitution of parts and changes in construction being resorted to as desired, it being understood that the embodiment shown in the drawings and described above is given merely for purposes of explanation and illustration without intending to limit the scope of the claims to the specific details disclosed.

What we claim is:

1. A canister assembly comprising in combination a casing formed with a bin receiving chamber and having an apertured upright sheet material wall but otherwise substantially completely sealed, a bin receivable in the casing chamber through the aperture in said wall, the upright wall including inwardly offset bin stop portions along the edges of the aperture, said bin having a top opening and sheet material front and bottom walls disposed substantially in intersecting planes, the front wall being larger than the casing aperture and marginally overlapping the bin stop portions of the upright wall, deformable strip means interposed between the margins of the bin front wall and the bin stop portions of the upright wall in sealing relation about substantially the entire extent of the aperture, pivot means supporting the bin for swinging movement about a substantially horizontal axis located in the angle between the front and bottom walls whereby the weight of the bin and its contents provides a turning moment about said axis gravitationally normally to hold the bin front wall yieldingly and sealingly against the upright casing wall and the interposed deformable strip means to maintain the aperture sealed, a closure for the bin opening, said bin closure being slidably and wholly supported on the bin and moveable with the latter to remain in sealing relation to the bin top opening as the bin is swung between a retracted position within the casing chamber and an extended position projecting through the casing opening, said bin closure being relatively moveable on the bin between open and closed positions to provide a seal supplemental to the casing aperture seal for the protection of the bin contents when the bin front wall engages the deformable strip means and the bin closure is in the fully closed position on the bin.

2. A canister assembly comprising in combination a casing formed with a bin receiving cham-

ber and having an apertured upright sheet material wall but otherwise substantially completely sealed, a bin receivable in the casing chamber through the aperture in said wall, the upright wall including inwardly offset bin stop portions along the edges of the aperture, said bin having a top opening and sheet material front and bottom walls disposed substantially in intersecting planes, the front wall being larger than the casing aperture and marginally overlapping the bin stop portions of the upright wall, deformable strip means interposed between the margins of the bin front wall and the bin stop portions of the upright wall in sealing relation about substantially the entire extent of the aperture, pivot means supporting the bin for swinging movement about a substantially horizontal axis, a closure for the bin opening, said bin closure being slidably and wholly supported on the bin and moveable with the latter to remain in sealing relation to the bin top opening as the bin is swung between a retracted position within the casing chamber and an extended position projecting through the casing opening, said bin closure being relatively moveable on the bin between open and closed positions to provide a seal supplemental to the casing aperture seal for the protection of the bin contents when the bin front wall engages the deformable strip means and the bin closure is in

5
